CLAIM

The ornamental design for a candle box, as shown and described.

DESCRIPTION

FIG. 1 is a perspective view of the candle box with the padded lid removed;

FIG. 2 is a top view of the candle box with the lid in place;

FIG. 3 is a bottom view of the candle box with the padded lid in place;

FIG. 4 is a top view of the candle box with the padded lid removed;

FIG. 5 is a bottom view of the padded lid of the candle box;

FIG. 6 is a side view of the candle box;

FIG. 7 is a side view of the candle box rotated 90 degrees;

FIG. 8 is a perspective view of the candle box with candle and padded lid removed; and,

FIG. 9 is a side view of the candle removed from the candle box.

The broken lines in figures showing a tassel attached to the candle box in FIGS. 1, 6 and 7 are for illustrative purposes only and form no part of the claimed design.
